US00D607402S

(12) **United States Design Patent**
Himedea

(10) **Patent No.:** **US D607,402 S**
(45) **Date of Patent:** **** Jan. 5, 2010**

(54) **BATTERY**

(75) Inventor: **Noriko Himeda**, Osaka (JP)

(73) Assignee: **Panasonic Corporation**, Kadoma-shi (JP)

(**) Term: **14 Years**

(21) Appl. No.: **29/308,649**

(22) Filed: **Jun. 27, 2008**

(30) **Foreign Application Priority Data**

Dec. 28, 2007 (JP) 2007-036188

(51) **LOC (9) Cl.** **13-02**

(52) **U.S. Cl.** **D13/103**

(58) **Field of Classification Search** D13/102-106, D13/110, 118-119, 184; 429/96-100, 163, 429/176

See application file for complete search history.

(57) **CLAIM**

The ornamental design for a battery, as shown and described.

DESCRIPTION

The file of this patent contains at least one figure executed in color. Copies of this patent with color figures will be provided by the Office upon request and payment of the necessary fee.

FIG. 1 is a perspective view of the front, top of a battery showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is an expanded view of the pattern that is formed on the battery.

1 Claim, 8 Drawing Sheets
(8 of 8 Drawing Sheet(s) Filed in Color)
